CONTAINER

Harry Sebell, Marblehead, Mass., assignor of one-half to Arthur H. Parker, Lexington, Mass.

Application September 10, 1942, Serial No. 457,810

1 Claim. (Cl. 215—46)

This invention relates to containers for packaging food and other products and it is especially adapted for a container having a glass body portion and a sheet metal end closure.

The features wherein my invention resides will be apparent from the following description and will be pointed out in the appended claim.

In the drawing:

Fig. 1 is a side view of a container embodying my invention.

Fig. 2 is a fragmentary sectional view on the line 2—2, Fig. 1.

Fig. 3 is a fragmentary side view of the container with a part broken out showing the end member applied to the body portion but not sealed thereto.

Fig. 4 is a section on the line 4—4, Fig. 1, looking toward the top of the container.

Fig. 5 is an enlarged fragmentary sectional view on the line 5—5, Fig. 1.

Fig. 6 is a view showing the blank from which the end closure is formed.

Fig. 7 is a fragmentary view illustrating the manner of opening the container by tearing out the tear strip.

Fig. 8 is an enlarged sectional view on the line 8—8, Fig. 7.

1 indicates the container body which may be of any suitable material but which will preferably be of glass or possibly plastic material. This container body is shown as having a relatively short neck portion 2 at its upper end which provides the opening 3 through which the container is filled and through which the contents thereof are discharged.

The neck 2 is provided at its top with an exterior bead having a cylindrical side wall, the under side of which bead provides a downwardly facing shoulder 4 which is situated a short distance below the top of the neck.

The end closure by which the container is sealed is indicated generally at 5, and it is preferably made of sheet metal. Said end closure is formed with a depending cylindrical skirt portion 6 which encircles and tightly fits the part of the neck above the shoulder 4, the lower edge of the skirt portion being crimped inwardly beneath the shoulder 4 as shown at 7.

In order to provide an hermetic seal for the container, I preferably employ a sealing gasket 9 between the top edge of the neck 2 and the closure member 5, and the central portion of the closure member may be depressed so as to provide the channel 8 to receive the packing 9, this

being a common expedient in containers of this type.

The container is constructed to be opened by tearing out a tear strip from the end closure 5, and for this purpose, the skirt portion 6 of the end closure is provided with a scoreline 10 which extends completely around the skirt at a point slightly above the shoulder 4.

The end closure is also provided with a tab 11 which is formed integrally with the closure and which has its length dimension, that is, the dimension from its tip to its base where it joins the skirt portion, extending parallel to the lower edge of the skirt, said tab being spaced from said lower edge of the skirt portion as shown at 12. The end closure is further provided with a branch scoreline 13 which extends from the encircling scoreline 10 to the edge of the inturned portion 7 at a point where the upper edge of the tab meets said edge.

The blank from which the end closure is made is shown at 5a in Fig. 5. This blank is circular in shape and has the tab 11 integral therewith. The blank is also formed with the circular scoreline 10 and with the branch scoreline 13 which extends from the scoreline 10 to the edge of the blank at the point where the upper edge of the tab meets the edge of the blank.

After the blank 5a has been blanked out from the sheet metal and the scorelines 10 and 13 have been formed in the blank, then said blank is deformed by means of dies to produce the end closure such as shown in Fig. 2 which is provided with the depending skirt 6. The dotted line 17 in Fig. 6 indicates where the blank 5a is bent to form the skirt portion of the end closure.

The end closure thus formed is then placed on the container as shown in Fig. 3, said container having previously been provided with the packing material 9, and the end closure is sealed to the container body by crimping the lower edge of the skirt inwardly beneath the shoulder 4. It will be understood that the skirt 6 as initially formed is long enough so that when the end closure is placed on the container neck, the lower edge of the skirt will extend slightly below the shoulder.

The crimping of the lower marginal edge portion of the skirt 6 underneath the shoulder 4 serves not only to lock the end member to the container but also to effect a tight seal between the end closure and the neck of the container.

This crimping operation not only bends the

lower marginal edge portion of the skirt underneath the shoulder as shown at 7 but it also bends the root portion 18 of the tab inwardly under said shoulder. This crimping operation brings the tab 11 underneath the shoulder 4 and into a position where it lies flatly against the outside of the container neck 2 and has its length dimension extending circumferentially of said neck.

The encircling scoreline 10 is situated slightly above the shoulder 4, and the upper portion of the branch scoreline 13 will extend from the scoreline 10 to the shoulder 4 as shown in Fig. 1 while the lower portion of said branch scoreline 13 will be in the portion of the skirt which is crimped in under the shoulder 4 as shown in Fig. 4.

The advantage of spacing the tab 11 from the lower edge of the skirt portion as shown at 12 is that said tab will be below and out of the path of the crimping wheel which is used for crimping the edge 7 of the skirt underneath the shoulder 4, and, therefore, said tab will not be distorted in any way by said crimping operation. This crimping operation, however, will force the tab into engagement with the exterior of the neck 2 so that the tab will lie closely against said neck and will be situated entirely beneath the shoulder 4. The tab is thereby protected by the shoulder, which is an advantage because it eliminates danger that the tab may be accidentally bent outwardly from the position shown in Fig. 4 during the handling or transportation of the sealed container.

This tab construction has the further advantage that it enables the container to be opened by a key element 14 of the usual type which is provided with a tab-receiving slot 15. To open the container, the free end of the tab 11 will be separated from the neck of the container as shown by dotted lines in Figs. 2 and 4 and then the key 14, while held in position substantially parallel to the container axis, is applied to said free end of the tab and is turned to wind the tab thereon. When the tab is completely wound on the key then further turning movement of the key will operate to tear the skirt, first along the branch scoreline 13 and then along the circumferential scoreline 10 thereby to tear off from the end closure the portion 19 of the skirt below the scoreline 10. This portion 19 thus forms a tear strip which is wound up on the key as it is torn from the end closure as indicated at 16 in Figs. 7 and 8.

During the first few turns of the key, the tear strip will be torn along the branch scoreline 13 as stated above and subsequently the tearing will take place along the encircling scoreline 10. Since the tear strip includes the inwardly

crimped edge portion 7 of the skirt 6, said tear strip will be curved transversely, and as it is wound up on the key into the roll 16, the inner or concave face of the tear strip will be presented 5 on the outside of the roll and each turn of the roll will thus be seated in the concave face of the preceding turn.

This is clearly indicated in Fig. 8. The advantage of this is that each turn of the roll 16 will be properly positioned in the roll by the preceding turn and the roll will be built up on the key without any danger that the turns of the roll will slip sidewise thus causing a collapse of the roll.

10 It will be noted that the encircling scoreline 10 is located in the lower portion of the skirt 6. The advantage of this is that, after the tear strip 19 has been torn out for opening the can, 15 the end closure will still have a skirt of sufficient depth to fit over the top of the container thereby making it a replaceable cover or closure.

I claim:

A container comprising a body portion having an open upper end and formed with a relatively short neck of reduced diameter at said upper end, said neck being provided at its upper end with an exterior bead having a cylindrical exterior surface, the under side of which constitutes a downwardly facing shoulder, and an end closure of sheet metal closing said open end of the container and provided with a cylindrical skirt portion which fits and encircles the cylindrical face of said exterior bead, the lower edge of the skirt portion being crimped inwardly beneath said shoulder, said skirt portion having a tab integral therewith, the length dimension of which from the tab tip to the base thereof where it joins said skirt portion extending substantially parallel to the edge of the skirt portion, said tab being situated below and spaced from said edge for its entire length, the radial dimension of said shoulder being considerably greater than the thickness of the tab, the width of the tab being less than the vertical dimension of said neck, whereby the tab is protected from above by said shoulder and from below by the body portion of the container where it joins the neck, said skirt portion also having an encircling scoreline extending completely thereabout at a point slightly above said shoulder and further having a branch scoreline extending from the encircling scoreline to the edge of the inwardly crimped portion of the skirt at the point where said edge meets the upper edge of the tab, the portion of the skirt below the encircling scoreline constituting a tear strip which can be torn from the end closure to open the container.

HARRY SEBELL.
